(57) **CLAIM**

The ornamental design for the truck trunk, as shown and described.

DESCRIPTION

FIG. 1 is a perspective view of the truck trunk showing my new design, shown in its position of use.

FIG. 2 is a front perspective view of the truck trunk.

FIG. 3 is a back perspective view of the truck trunk.

FIG. 4 is a right side view of the truck trunk.

FIG. 5 is a front elevational view of the truck trunk.

FIG. 6 is a left side view of the truck trunk.

FIG. 7 is a top plan view of the truck trunk.

FIG. 8 is a bottom plan view of the truck trunk; and,

FIG. 9 is a rear elevational view of the truck trunk.

The broken line showing of environment is for illustrative purposes only and forms no part of the claimed design.
